UNITED STATES PATENT OFFICE.

ALBERT C. MURPHY, OF NEW YORK, N. Y.

DUMPING-CAR.

1,232,959.

Specification of Letters Patent. Patented July 10, 1917.

Application filed October 20, 1915. Serial No. 56,936.

To all whom it may concern:

Be it known that I, ALBERT C. MURPHY, a citizen of the United States, and resident of New York, county of New York, and State of New York, have invented an Improvement in Dumping-Cars, of which the following is a specification.

The object of my invention is to provide a suitable construction of dumping car having hinged side doors and operating mechanism therefor, whereby the tilting operation of the body will automatically cause the door on the depending side to open into discharging position, and during the righting of the body into its normal horizontal position, and to provide in a dumping car, locking means which normally lock the doors when the body is in the normal horizontal position and which automatically release the doors during the preliminary portion of the tilting period of the body so as not to interfere with the positive opening of the doors, and yet which will assist in holding the doors in locked position when the body is in its normal horizontal positions during the travel of the car, said means to have capacity for permitting the door releasing means to be adjusted out of automatic action whereby the latches may be released by hand operation in the dumping position where it is desired to discharge only a portion of the load, it being understood that when this provision is made the body is provided with a plurality of doors on its side.

My object is further, to provide guiding chutes or aprons on the sides of the car and so arranged that they are moved into inclined position when the body is tilted to dumping position, the said aprons being hinged and operatively associated with the locking mechanism of the doors that said mechanism operates to hold the aprons from swinging outward from the side of the car at all times except when the locking mechanism is being operated for releasing the doors preliminary to or during the dumping operation.

My object is further, to provide a dumping car with side doors hinged at the top and having their lower portions so shaped as to provide a joint with the body which shall present an extended surface frictionally in contact when in closed position to provide a non-leakable joint.

With the above and other objects in view,

the nature of which will be more fully understood from the description hereinafter, the invention consists in the novel construction of dumping cars as hereinafter more fully described and defined in the claims.

Referring to the drawings:—

Figure 1 is end elevation, with part in section, of a dumping car embodying my invention, the truck thereof being omitted;

Fig. 2 is a side elevation of one end of a dumping car embodying my invention;

Fig. 3 is a cross section of my improved car showing the special constructions adjacent to the locking means for the door etc.; and

Figs. 4, 5 and 6 are cross sections of details showing the means of supporting the apron and the locking mechanism for the doors.

2 is the longitudinal girder frame, which is ordinarily supported upon the trucks (not shown) and said girder frame is provided at intervals with rocker beds 5 on its upper part, with which the rockers 4 engage, said 30 rockers attached to and supporting the body 3. By this construction, the body may be rocked upon the girder frame and brought into a tilted position to either side of the car, as may be desired, one of said tilted 85 positions being indicated in dotted lines in Fig. 1.

The body 3 has longitudinal girder irons 17 along its lower outer side edges and similar irons 16 along its upper outer side portions, the space between said girder irons 16 and 17 being open except in so far as it may be closed by hinged doors 15, of which there may be one or more on each side of the car. The girder iron 16 is provided with 95 bearing 12 carrying a hinge rod 14 upon which the doors 15 are hinged at 13, said doors arranged to swing outward at the bottom during the dumping operation. The longitudinal girder irons 17 at the lower 100 side edges of the body support the flow plates and also carry the bearing castings or parts 29 in which the rock shaft 23 is journaled, said shaft operatively carrying the latch hooks 24 for engaging the doors 105 when they are to be held in closed position. As shown, these irons 16 and 17 are L-shaped in cross section, but I do not confine myself in this respect.

The body 3 has its ends greatly higher, 110 at the middle than at the sides adjacent to the girder irons 16 so that the load may be

heaped up at the longitudinal middle portion of the body, while employing a minimum available height of door 15 for a given maximum load to be carried. While I prefer to shape the ends of the car body as shown in Fig. 1 for this purpose, it will be understood that this is not essential, as it will suffice to have the ends extend sufficiently above the doors for the purpose without leveling off the outer upper portions for appearance, as has been done in the particular illustration of this application. In those cases where there are a plurality of doors 15 on each side to be employed, the body may be divided transversely by division plates or partitions 3^a to be arranged intermediate of adjacent doors so that the opening of a door will cause only a portion of the whole load to be discharged. These partitions are riveted both to the floor and to the upper girder irons 16 and act as braces to the floor and the door supports. The door 15 may have their ends provided with inwardly extending wings 21 which act as side guides for the discharging contents. When the doors are permitted to swing outwardly, said wings extending down close to the floor plates are curved to maintain this relation during the normal action of the doors. It will be further observed that the lower edges of the doors are bent inward and braced by bracket portions 22 (Fig. 3). It will also be seen that to this inwardly directed portion there is secured a special U shaped portion 18 which greatly strengthens the lower edge of the door and further provided an inclined lower seating flange 19, whose inner portion alines with the lateral edge of the floor plate and whose outer portion inclines downwardly and outwardly and preferably slightly tangential to a curve about the hinge rod 14 as a center. Riveted to this lower portion 18 of the door and preferably located adjacent to the middle of its length, is the latch frame 20, desirably formed of a casting and having a suitable hole through which the lock or latch hook 24 passes for engagement when locking the door in closed position (Figs. 1 and 3). 30 is a longitudinal sill plate bolted at 30^a to the bearing brackets 29 (which are riveted to the girder iron 17) and having its upper part inclined inward toward the girder iron 17 and held in position thereto by suitable lugs 30^b. This sill plate 30 presents an inclined surface against which the tangential portion 19 of the door makes close surface contact to form a tight or non-leaking joint when the door is closed. The tightness of the joint at the bottom is supplemented by the use of the wings 21 on the ends of the doors, they forming close fitting parts around which the contents of the car can not work. It will thus be seen that this construction of door is very effective for use where the load is of subdivided or loose material such as sand, dirt, marl or other substance in a fine state of subdivision. It will also be noted that the sill plate 30 is removable, so that it may be replaced when worn. When the door is closed the weight thereof will cause the part 19 to seat positively upon the sill plate 30 and no normal wear of the hinges of the door will interfere with the tightness of the joint thus provided. 70

23 is a longitudinal latch operating shaft journaled in the bearing brackets 29, and has at its end a lever 47 by which it may be rocked by hand; and said lever is also provided with a special shaped slotted arm, the slot of which comprises the parts 44, 45 and 46, as clearly shown in Figs. 5 and 6. The slot parts 44 and 45 form abutment sockets for a pin 48 of a toggle lever 42 and the part 46 forms a communication between said parts 44 and 45 whereby the pin may be transferred from one part to the other, as shown in these figures. 80

The toggle lever 42 is hinged at 40 to the free end of the toggle lever 41 which latter has its other end hinged to the main or girder frame 2 at 48. (Fig. 1.) When the car body is in its horizontal or non-dumping position the toggle levers 41 and 42 are suspended as shown at right side of Fig. 1; but when the body is tilted into dumping position as shown in dotted lines, the toggle levers at the rising side open out to provide the reach to maintain connection with the lever 47, while the toggle levers on the dumping side form a strut to automatically operate the lever 47 and rock the shaft 23 to release the doors on the dumping side. In doing this, the angle toggle bar 41 comes into contact with the girder frame 2 and thereafter the bar 42 acts as a radius bar hinged at a fixed axis and hence operates as a strut to force the lower end of the lever 47 outward and rock the shaft 23 as will be readily understood. When the doors are to be automatically unlatched for dumping during the tilting operation the pin 43 is adjusted in the slot 44 as shown in Figs. 1 and 6, as in that case the greatest oscillation is given to the lever 47 and rock shaft 23. On the other hand, when the doors are to be released by manual operation, the pin 43 is adjusted into the slot 45 as shown in Fig. 5, as in this case only a partial oscillation of the lever 47 and rock shaft 23 is required and then only to release the latches 24 and the aprons 25, whereby the former may be lifted by hand and the latter automatically oscillated into inclined position as shown in dotted lines in Fig. 1. 100

The rock shaft 23 is fitted with the latches 24 in such manner that they are rotatable through a given arc and this is provided by them having slots 28 in their hubs into which 105

110

115

120

125

the heads and nuts of the bolts 27 extend, said bolts passing through and moving with the rock shaft 23 (Figs. 5 and 6). It will be seen from Fig. 5 that the latch 24 may be lifted at its hook end in the act of releasing or unlocking the door 15 by hand, whereas in the adjustment shown in Fig. 6 the door would be unlocked automatically by an oscillation of the rock shaft during the tilting of the car body, the rock shaft being given so great an oscillation that the bolt 27 will strike the opposite ends of the slots 28 and positively oscillate the latches 24. In the adjustment shown in Fig. 5 the tilting of the body will not move the rock shaft sufficiently to cause the latch 24 to be raised automatically. By this capacity for either automatic or hand releasing of the doors, it is possible to dump the entire content of the body at one operation, or only dump the content of a single compartment from one door passage as desired.

The apron 25 has hinge parts 26 by which it is suspended and these parts are journaled on the rock shaft 23, as shown in Figs. 3 and 4. The hub parts 26 have slots 28^a corresponding to the slots 28 in the latches and the rock shaft 23 has bolts 27^a whose heads and nuts extend into the slots and engage the ends thereof. When the car body is horizontal (Fig. 3), the apron rests upon the spring stops 31 by which it is prevented from swinging inwardly; and it will also be observed that the ends of the slots 28^a abut against the bolt heads 27^a on the rock shaft 23, so that the apron cannot swing outwardly during the transportation of the car so long as the rock shaft is locked against rotation. In this way the apron is held in a fixed position. In practice, the rock shaft 23 is normally held in the position indicated by the hand lever 47 being frictionally locked by the latch spring 47^a (Figs. 1 and 2). This spring is made of a piece of flat spring steel provided with a shoulder back of which the lever snaps when the upper end is pulled outward, and by which it is held with sufficient friction to normally retain its locking position. Any other suitable lock or latch may be employed for holding the lever 47 in position. It will be understood that when the lever 47 is rocked by the mechanical devices herein before described during the tilting operation of the body, the rock shaft 23 will be shifted from the position shown in Fig. 6 to the position shown in Fig. 5, if the pin 43 is in the socket portion 45 as indicated in the latter figure, and to a greater extent if said pin is in the socket 44, and in either case the apron 25 is released so that it may be moved out into an oblique position as indicated in dotted lines (Fig. 1). This latter action takes place whether the body is to be automatically dumped by the auto-

matic operation of the latches 24 (by adjustment of pin 43 shown in Fig. 6) or is to be manually dumped by hand operation of the latches (when the pin 43 is in the adjustment indicated in Fig. 5), for in either case the apron performs the same function.

It will now be apparent that I have devised a novel and useful construction which embodies the features of advantage enumerated as desirable, and while I have in the present instance shown and described the preferred embodiment thereof which has been found in practice to give satisfactory and reliable results, it is to be understood that I do not restrict myself to the details, as the same are susceptible of modification in various particulars without departing from the spirit or scope of the invention.

Having now described my invention, what I claim as new and desire to secure by Letters Patent, is:—

1. In a dumping car, the combination of a main frame, with a tilting body supported upon the main frame with capacity for rocking transversely, a hinged door at the side of the body and adapted to swing outwardly at the bottom, an apron hinged adjacent to the lower outer edge of the body and adapted to be swung outwardly when the body is tilted to act as a chute over which the contents is dumped, a latch for locking the hinged door in a closed position, and common means for holding the latch in locked position and also locking the apron against swinging outwardly.

2. In a dumping car, the combination of a main frame, with a tilting body supported upon the main frame with capacity for rocking transversely, a hinged door at the side of the body and adapted to swing outwardly at the bottom, an apron hinged adjacent to the lower outer edge of the body and adapted to be swung outwardly when the body is tilted to act as a chute over which the contents is dumped, a latch for locking the hinged door in a closed position, means for holding the latch in locked position and the apron against swinging outwardly, automatic means under the control of the tilting body for operating upon the said means to release the latch and liberate the apron, and means to automatically move the free end of the apron outwardly when said apron is released.

3. In a dumping car, the combination of a main frame, a body supported upon the main frame and adapted to be tilted laterally thereon, a door hinged to the side of the body and having its lower end adapted to swing outwardly when the body is tilted, a rock shaft carried by the body, latches for locking the door in a closed position said latches arranged to be held in locking position by the rock shaft, and operating means for the rock shaft connected with the main

frame for giving said rock shaft a large or small rocking motion as predetermined by adjustment during the tilting action of the body, whereby the latch may be automatically operated to the full extent to release the door for automatic dumping or may be released to a minor extent so as not to automatically release the door but to permit the latch to be manually operated after the tilting operation of the body to cause the dumping of the contents under the direct control of the operator.

4. In a dumping car, the combination of a main frame, a body supported upon the main frame and adapted to be tilted laterally thereon, a door hinged to the side of the body and having its lower end adapted to swing outwardly when the body is tilted, a rock shaft carried by the body, latches for locking the door in a closed position said latches arranged to be held in locking position by the rock shaft, and operating means for the rock shaft connected with the main frame for giving said rock shaft a large or small rocking motion as predetermined by adjustment during the tilting action of the body, said means consisting of a lever secured to the rock shaft and having two socket portions arranged at different points circumferentially in respect to the axis of the rock shaft, and a radius bar mechanism having one end supported by the main frame and the other end provided with means adapted to engagement with either of the sockets to give a greater or less rocking motion to the lever during the tilting operation, whereby the latch may be automatically operated to the full extent to release the door for automatic dumping or may be released to a minor extent so as not to automatically release the door but to permit the latch to be manually operated after the tilting operation of the body to cause the dumping of the contents under the direct control of the operator.

5. In a dumping car, the combination of a main frame, a body supported thereon and arranged to be tilted laterally for dumping, a door hinged at the side of the body and adapted to have its lower end swing outwardly, a pivoted latch adapted to engage the door to hold it in locked position, a rock shaft carried by the body and adapted to engage the latch to hold it in locked position or operate it to release the door as required, an apron hinged to the bottom of the body at a point below the door, an adjustable strut to cause the lower end of the apron to swing outwardly when the body is tilted, means controlled by the rock shaft for holding the apron from swinging outwardly when the body is in its normal position, and means for operating the rock shaft for releasing the apron and the latch.

6. In a dumping car, the combination of

a main frame, a body supported thereon and arranged to be tilted laterally for dumping, a door hinged at the side of the body and adapted to have its lower end swing outwardly, a pivoted latch adapted to engage the door to hold it in locked position, a rock shaft carried by the body and adapted to engage the latch to hold it in locked position or operate it to release the door as required, an apron hinged to the bottom of the body at a point below the door, an adjustable strut to cause the lower end of the apron to swing outwardly when the body is tilted, means controlled by the rock shaft for holding the apron from swinging outwardly when the body is in its normal position, and means for operating the rock shaft for releasing the apron and the latch, said means consisting of a lever secured to the rock shaft, means to hold the lever in locked position when the body is in horizontal position and connecting means between the main frame and the lever for automatically rocking the lever when the body is tilted so that the apron and the door are both simultaneously released when the body is tilted.

7. In a dumping car, the combination of a main frame, a car body supported thereon with provision for being tilted laterally into dumping position, a discharge opening and door on the side of the body, a longitudinal rock shaft journaled in bearings at the side and lower part of the body, an apron hinged to the rock shaft and extending downwardly, a support extending from the body to hold the apron against abnormal inward movement at its free end, locking means controlled by the rock shaft to hold the apron against outward movement at its free end when the body is in a horizontal position, and adjustable strut means between the main frame and the apron for moving the free end thereof outwardly when the body is tilted into dumping position whereby the apron acts as a chute for the discharge of the contents of the body.

8. In a dumping car, the combination of a main frame, a car body supported thereon with provision for being tilted laterally into dumping position, a discharge opening and door on the side of the body, a longitudinal rock shaft journaled in bearings at the side and lower part of the body, an apron hinged to the rock shaft and extending downwardly, a support extending from the body to hold the apron against abnormal inward movement at its free end, locking means controlled by the rock shaft to hold the apron against outward movement at its free end when the body is in a horizontal position, adjustable strut means between the main frame and the apron for moving the free end thereof outwardly when the body is tilted into dumping position whereby the

apron acts as a chute for the discharge of the contents of the body, and automatic means between the main frame and the rock shaft for operating the same to remove the 5 operation of the locking devices whereby the apron is released and may be swung outwardly when the body is tilted.

9. In a dumping car, the combination of a main frame, with a body supported thereon 10 and arranged to be tilted laterally, a side door for the body for controlling the discharge of the contents, a rock shaft journaled at the lower side of the body, a latch carried by the rock shaft and engaging the 15 door to hold it in locked position, mechanical devices between the rock shaft and the latch for holding the same in either unlocked position or locked position or releasing the latch so that it may be operated 20 by hand according to the extent of rotation of the rock shaft, a lever secured to the rock shaft and having two sockets at a distance apart, and a radius bar connected with the main frame and having a pin adapted to 25 either of the socket portions to vary the extent of movement of the lever for moving the latch to its fully unlocked position or for releasing it so that it may be hand operated when the body is tilted.

36 10. In a dumping car, the combination of a main frame, with a body supported thereon and adapted to tilt laterally into dumping position, a door hinged to the side of the body and having its lower end free 35 to swing, a longitudinal shaft arranged at the lower side edge of the body, a latch journaled upon the rock shaft for engaging the door to hold it closed said latch having its hinge portion slotted, means projecting from 40 the rock shaft into the slotted portion for engaging the latch for holding it closed or for raising it to release the door, a lever secured to the rock shaft for operating it and provided with a slotted portion having at 45 each end a socket, said sockets circumferentially separated with respect to the axis of the rock shaft, a radius bar having a joint connection at one end provided with a pin extending into the slot of the lever and 50 adapted to be adjusted to either of the sockets, whereby, according to the adjustment of the pin in the sockets, the latch may be released but not moved to unlock the door or may be positively moved to unlock the 55 door by the automatic tilting operation of the body.

11. In a dumping car, a main frame, combined with a body supported thereon and adapted to tilt laterally said body having 60 end plates having their middle portions extended to a height considerably above the sides of the body whereby the body will hold a heaped up load higher than the height of the sides of the body, longitudinal upper 65 side girder irons connecting the upper and

outer sides of the end plates and providing lateral side openings between said side girder irons and floor of the body, doors hinged at their tops to the girder irons, means for detachably holding the doors in 70 locked position, and means for tilting the body.

12. In a dumping vehicle, the combination of a main frame, a body supported thereon with capacity for being tilted laterally into 75 dumping position said body having a discharge opening on its side the bottom of which is provided with an inclined sill plate, a door hinged to the upper portion of the body and closing over the side opening there- 80 in and having its lower part provided with a plate formed with an inclined seating flange adapted to seat upon the inclined sill plate, and locking means for holding the door in closed position. 85

13. In a dumping vehicle, the combination of a main frame, a body supported thereon with capacity for being tilted laterally into dumping position said body having a discharge opening on its side the bottom of 90 which is provided with an inclined sill plate detachably clamped in position, a door hinged to the upper portion of the body and closing over the side opening therein and having its lower part provided with a rein- 95 forcing sealing plate formed with an inclined seating flange at its bottom adapted to seat upon the inclined sill plate, and locking means for holding the door in closed position. 100

14. In a dumping vehicle, the combination of a main frame, a body supported thereon with capacity for being tilted laterally into dumping position said body having a discharge opening on its side the bottom side 105 edge of which is inward of the general side of the body, a replaceable inclined sill clamped to the said lower edge of the body and extending outwardly and downwardly to approximately the full width of the body, 110 a door hinged to the body at the upper part of the side opening and inwardly inclined at the bottom and provided with a seating flange extending downwardly and outwardly to form a close joint with the inclined sill of the body. 115

15. In a dumping vehicle, the combination of a main frame, a body supported thereon with capacity for being tilted laterally into dumping position said body having a discharge opening on its side the bottom side edge of which is inward of the general side of the body and provided with sockets, a replaceable inclined sill fitting the 120 sockets and clamped to the said lower edge 125 of the body and extending outwardly and downwardly to approximately the full width of the body, a door hinged to the body at the upper part of the side opening and inwardly inclined at the bottom and provided 130

with a seating flange extending downwardly and outwardly to form a close joint with the inclined sill of the body, and locking means extending from the body through the sill and engaging the door to hold it closed.

16. In a dumping vehicle, a body having the side edge of its floor terminating at a point inward of the general side of the body, and provided with a plurality of brackets secured thereto, a rock shaft journaled in the brackets and parallel to the lower side edge of the floor, a door hinged to the side of the body and having a lower inwardly directed portion terminating in an outwardly and downwardly directed seating flange, a sill clamped to the brackets and having at its upper portion an inclined part directed to-

ward the side edge of the floor of the body and upon which the door seats, said door having a downwardly projecting keeper, a 20 latch carried by the rock shaft and extending through the sill and the keeper for locking the door in closed position, and means for rocking the rock shaft, the construction being such that the rock shaft is protected 25 from discharging dirt from the body and shielded from view.

In testimony of which invention, I hereunto set my hand.

ALBERT C. MURPHY.
